UNITED STATES PATENT OFFICE

ALFRED G. F. KUROWSKI, OF BROOKLYN, NEW YORK, ASSIGNEE TO UNDERWOOD
ELLIOTT FISHER COMPANY, OF NEW YORK, N. Y., A CORPORATION OF DELAWARE

TYPEWRITING MACHINE

Original application filed April 24, 1924, Serial No. 708,633. Divided and this application filed February 4, 1930. Serial No. 425,756.

This invention relates to improvements in typewriting machine carrying cases, and particularly to types commonly known as portables, in which the machine is normally enclosed within a case adapted to be conveniently carried by hand.

One of the objects of the invention is to provide a two-part, separable case in which the cover element may be positively and safely secured to the base in such manner as to efficiently protect the machine from intrusion, damage, dust or moisture, under ordinary conditions of transit or storage, or permit the ready removal of the cover to allow authorized use of the machine, either as affixed to the base element of the case or removed operably intact therefrom.

Another purpose is to produce a carrying case base provided with means which operate effectually in minimizing, reducing and preventing the transmission of sound, incurred by operation of the machine, absorbing air-carried sound vibrations to a marked degree.

A further aim is in the provision of an unusually light, strong and compact carrying case of pleasing design, readily portable and having a base wall suited as a support upon which the machine may be conveniently operated, while acting as a silencer for any sound produced.

This application is a division of my application Serial No. 708,633, filed April 24, 1924.

Other features and advantages will hereinafter appear.

In the accompanying drawings,

Figure 1 is a longitudinal sectional view of an embodiment of the invention, illustrating the relation of parts to a conventional typewriter shown in broken lines within the case.

Figure 2 is a fragmentary sectional view taken in a plane represented by the characters Z—Z of Figure 1.

Figure 3 is a fragmentary sectional view taken on line X—X of Figure 2.

Figure 4 is a similar view taken on line Y—Y of Figure 2.

Figure 5 is another like view taken on line W—W of Figure 1.

Figure 6 is a partial plan view of the base

of the finishing frame of the typewriter in detail.

Figure 7 is a front elevational view of the same.

Figure 8 is a fragmentary sectional view taken on line V—V of Figure 6.

Figure 9 is a partial sectional and partial side elevational view of one of the inner frame feet, drawn to an enlarged scale.

The portable typewriter, shown in Figure 1 and designated generally by the numeral 10, is standard in all respects and constitutes a complete commercial entity.

The carrying case is composed of a top or front plate 15, preferably made of well-seasoned wood, as is also the bottom or base plate 16. An integral piece of sheet-metal is formed to present side walls 17 and a cover 18, inclined downwardly at the front 19 and having inwardly-curved edges 18' engaged in corresponding recesses in the upper and end edges of the plates 15 and 16, to which the cover-plate is rigidly secured, and the entire outer surface of the casing is insheathed in leather.

A strap handle 20 is provided on the top plate 15 for convenience in carrying, and a lock, generally designated by the numeral 21, is furnished to provide security from unwarranted intrusion.

Fixed near each of the four corners of the bottom plate are button-headed nails 22 or the like to protect the leather-covered surface of the casing when resting on its bottom or lower end, the foregoing elements constituting the cover or removable portion of the case.

The base-portion is composed of a wooden frame 23 formed from quarter-round molding with mitered joints, freely receivable within the lower portion of the cover.

A metal plate 24 is secured to the flat lower surface of the frame 23, and is provided on its lower exposed side with a leather covering, from which extend four cushion elements, as the rubber feet 25, held in rigid engagement by cement or like adhesive.

The rear member of the frame 23 contains recesses 26 adjacent its ends, these recesses having metallic linings 27 suited to be engaged by a pair of hooks 28, fixed to the inner

surface of the bottom plate 16, and adapted to interlock with the linings to removably engage the rear end of the base within the cover, as best shown in Figure 3.

5 Set midway in the length of the front member of the frame 23 is a button-headed stud 29 projecting to interlock with a spring latch incorporated in the lock 21, see Figure 1, thus co-operating with the hooks 28 at the opposite 10 end to securely lock the cover to the base, constituting a single carrying unit.

The typewriting machine 10, as indicated in Figure 1, is composed of a pair of ribbon-spool housings 51 and a curved dust-guard 52.

15 The brackets 53 for the housings 51 together with said housings and the dust-guard 52 co-operate to provide dust-guards for the front links (not shown) of the type-action and the type-heads (not shown). Cast side 20 frames 11 having extending base pads 12 serve as feet during assembly of the machine, the same being drilled and tapped, as shown in Figure 8, to receive temporary rubber feet.

The typewriter frame sides 11 terminate, as 25 shown in Figure 1, at the inner row of the key-levers to define a machine base area, but affording no protection to the bank of keys, and it would obviously add greatly to the weight of the frame and casing if it were continued around the keyboard in the usual manner.

The present invention contemplates the formation of a separate enclosing finishing frame 54 or silencing pocket shaped by power 35 press methods from a single piece of sheet-metal to produce opposed side walls 30 and rear wall 31, all of which have inwardly-curved or rounded-over upper edges 30' and 31', presenting a smooth and agreeable finish, 40 and serving as dust-guards for the encased portion of the typewriting machine.

The front wall 32 is shaped in conformity with the general contour of the keyboard, which is enclosed by it at the front and sides, 45 and is provided with an inreaching ledge 32'.

The lower edges of the finishing frame are flanged inwardly, presenting a continuous ledge 33, the sides being stiffened by a cross-bar 34 disposed in the plane of the ledge 33.

50 A base-plate or floor 35 is riveted to the ledge 33, along the side and rear walls, and also to the cross-bar 34, this plate having a uniform shallow central depression 36 operating to stiffen the plate, affording a closure 55 for the base of the machine and space for the operation of the machine parts, and increasing the rigidity of the structure as a unit.

The base-plate may be provided with openings 37 arranged in any preferred manner, as 60 indicated in Figure 6, and near its corners is provided with openings 38 registerable with the openings in the feet 12 of the machine. The function of these openings is to break the base which would otherwise be the same as 65 the sound-producing diaphragm of a drum.

These openings materially reduce the noise which would result if the base were left as a continuous diaphragm.

Secured to the inner surfaces of the enclosing finishing frame walls is a relatively thick 70 layer of soft porous felt 39, the same acting to absorb sound emanations, which would otherwise be transmitted to the supporting base.

The upper surfaces of the ledge 33, cross-bar 34 and entire base-plate 35 are similarly 75 covered with a like but thinner felt fabric 40, and thus, when the machine is set in the enclosing frame, its feet rest upon the lined surface 40.

The feet 41, shown in detail in Figure 9, 80 consist of a cylindrical rubber block having an inverted conical top portion 42 disposed within a drawn metallic cup 43, provided with a pressed-in or riveted screw-threaded stud 44 suited to engage in the pads 12 after passing through the openings 38 in the casting base-plate.

In order to secure the feet 41 to the base of the carrying case and prevent any relative shifting movement, flanged metallic rings 45 90 are fixed in appropriate locations in the base, these rings being receptive of the feet and which are positively but removably held therein by the following means.

Extending oppositely outward from the 95 sides 30 of the finishing frame are rigid studs 46 having rounded outer ends, these studs being suited to engage in openings formed through latch-elements 47, pivotally supported in brackets 48, fixed on the base-plate 24, 100 as best seen in Figure 4.

The outer ends of the latches are curved to provide finger-holds and their inner ends project beyond their pivotal points to engage the free end of a spring detent 49 riveted to the plate 24 and extending below the pivot in the bracket 48, the detent being so shaped and arranged as to hold the latch 47 in either a raised, operatively engaging, position or when turned down to clear the studs 46.

110 These latches are readily accessible when the cover of the carrying case is removed and are operable by hand only, no tools being required to release the machine from the base.

As a further factor in rendering the machine substantially noiseless, when used upon the base of the carrying case, the base may be provided with a thick layer of felt 50 on its entire upper surface, the same preventing 115 transmission of sound.

It will be noted that the two side frames 11 are machine standards to promote the assembly of the parts and establish a machine-base area that does not include the keyboard; that the assembled machine is enclosed by a highly polished finishing frame which also includes a forward extension to protectively enclose the keyboard of the machine; that the enclosing finishing frame is formed with a floor-section of substantially the same area as the 120 125 130

established base of the machine to enclose the machine on the under side; that the finishing frame is attached to the machine side frames by cushioning feet; that the finishing frame 5 is lined throughout with felt to form a sound-absorbing pocket; that the finishing frame is secured to a sound-absorbing baseboard; and that the sound-absorbing baseboard primarily is a unit of the typewriting machine to increase the base-area of the machine when in 10 use and only coacts with the cover when the machine is not in use or being carried from place to place.

It will also be seen that the carrying case, 15 being formed with a sheet-metal base-plate for the typewriting machine and a sheet-metal opposite side wall for the cover, provides a carrying case having a minimum thickness, materially reducing the thickness 20 of carrying cases in which the corresponding walls are formed of wood or other compositions. The arrangement permits the sheet-metal walls to be spaced a minimum distance apart, with sockets to receive the feet of the 25 typewriter, so that they will rest directly upon the base. It will be noted that the typewriting machine with its outer finishing frame resting upon the base-plate, provides a chambered pocket between the bottom of the 30 finishing frame of the typewriter and the base-plate into which sounds emitted through the bottom of the finishing frame are received. This arrangement permits the positioning of a sound-absorbing padding on the 35 base-plate to further deaden the sounds which enter this chambered pocket. The padding extends over the base-plate between the sockets for the feet of the machine and the flanges or frame-members 23 of the base 40 without necessitating an increase in the space between the two walls.

To assemble the typewriting machine 10 with the frame 54, the latter, which has been previously polished, is arranged upright on 45 base-plate 35, whereupon the completely assembled typewriting machine 10 is inserted downwardly into the frame 54, as shown in Figure 1. When the machine 10 and the frame 54 are assembled as shown, the openings 50 of pads 12 align with the openings 38 of base-plate 35 so that the studs 44 are readily screwed into the pads to secure the feet 41 and frame 54 to the typewriting machine.

55 Variations may be resorted to within the scope of the inventions, and portions of the improvements may be used without others.

Having thus described my invention, I claim:

60 1. A sound-absorbing finishing mask for a portable typewriting machine frame having attaching feet, said mask comprising an outer frame to surround the lower portion of a typewriting machine frame but spaced 65 therefrom, said outer frame comprising side,

back and front portions and a base, said base including a stiffening bottom plate extending from the back portion forwardly and connecting the side portions but leaving an open space between said base and the front of the frame, said outer frame having means for attaching it to the feet of the typewriter-frame and linings of soft fibrous material upon said bottom plate and filling the space between said mask and typewriter-frame, and forming a sound-absorbing pocket. 70

2. In a portable typewriting machine having a main frame, a finishing mask enclosing the main frame and the lower portion of the typewriter, including the keyboard thereof, said mask having inturned edges at the top and inreaching flanges at the bottom, a floor secured on the flanges, said floor having a central depressed portion and containing openings registerable with the foot-attaching openings in the typewriter, and means for removable engaging said mask to the base 80 of the main frame.

3. In a portable typewriting machine having a main frame, a finishing mask enclosing the main frame and the lower portion of the typewriter, including the keyboard thereof, said mask having inturned edges at the top and inreaching flanges at the bottom, a floor secured on the flanges, a layer of felt fixed on 90 the inner surfaces of said mask and its floor, said floor having a centrally depressed portion containing corner perforations, and cushion foot-carrying elements having threaded studs passing through the mentioned perforations to engage in the foot-pads of the machine. 95

4. In a portable typewriting machine having a main frame, a finishing mask enclosing the main frame and the lower portion of the typewriter, including the keyboard thereof, a bar extending between the sides of said mask, a plate fixed on said bar and on inreaching flanges at the rear and sides of the mask, noise-absorbing linings on the inner surfaces 105 of said mask and plate, and means associated with the feet of the typewriter for clamping the plate thereto. 110

5. A portable typewriting machine having 115 a double frame consisting of inner supporting and outer masking members, the inner frame-member supporting moving parts of the machine, the outer frame-member being formed with a continuous overhanging flange extending around the sides, and front of the mask, sound-absorbing padding arranged under said flange and occupying the space between said frames at the sides thereof, and means whereby the frames are secured together. 120

6. As a new article of manufacture, a sound-absorbing finishing mask for attachment to a portable typewriting machine, including an outer mask-member struck up 130 from sheet-metal to surround the sides and

front of the machine, and having a floor to extend thereunder to serve as a brace and to form a sound-absorbing pocket, and a sound-absorbing padding secured in said mask-
5 member for packing against the sides of the typewriting machine.

7. A portable typewriting machine having an inner supporting frame-structure for the operating parts of the typewriting mecha-
10 nism and from which the keyboard forward-
ly extends, and a finishing frame therefor in-
cluding side walls extending around said supporting frame-structure and the forward-
ly-extending keyboard and a floor extending
15 under said supporting frame-structure of the typewriting machine, thereby forming a sound-absorbing pocket for encasing the noise-producing parts of the typewriting mechanism, a sound-absorbing material be-
20 ing lined between the inner frame-structure and the finishing frame.

8. A typewriting machine of the portable class provided with relatively movable parts including a platen and keys, and having a
25 skeleton self-sustaining main frame for en-
tirely supporting said parts, said keys occu-
pying a position in front of the skeleton frame, a surrounding casing complementary
30 to said frame and pressed from thin sheet-
metal into a shape to embrace the frame and
constitute an outer decorative mask applied
upon said self-sustaining main frame, said
mask including side portions below the platen
35 and masking the sides of said frame but
spaced and disconnected therefrom, a back
masking portion at the rear of said machine,
and a front portion inclining downwardly
to mask the front of said frame and extend-
40 ing around and forwardly of said keys, said
mask having a bottom member rigidly con-
nected to said side members to brace the same,
all of said side, back and bottom members
provided with sound-absorbing linings to
45 form a sound-subduing pocket, and said mask
being structurally independent of said frame,
and means for fastening said mask to the
bottom of said frame.

9. A typewriting machine of the portable class provided with relatively movable parts
50 including a platen and keys, skeleton self-
sustaining main side frames for supporting
the same, said keys occupying a position in
front of the skeleton frames, and a surround-
55 ing casing complementary to said frames and
shaped to embrace the frame but spaced and
disconnected from the sides thereof and con-
stituting an outer decorative mask for the
portable typewriting mechanism, said mask
60 being pressed from thin sheet-metal and hav-
ing inturned flanges at its edges and includ-
ing side portions masking the sides of said
frames, and having a front masking portion
65 extending downwardly from the front of said
frames and having an extension around and
forwardly of said keys, said mask being struc-

turally independent of said frames, and
means for fastening the mask to said frames.

10. A typewriting machine of the portable class having a self-sustaining skeleton main frame structure and relatively movable type-
writing mechanism supported on said frame structure, a decorative encircling mask formed from sheet-metal and with its sides separated and spaced from the frame structure and including side and rear walls and
70 a front enclosing said frame structure, said side walls having inwardly-extending flanges, a bottom attached at its edges to said flanges to support said side walls and extending from the rear forwardly but leaving an open space at the forward end of the mask, and means for fastening said bottom with the flanges to said frame.

11. A typewriting machine of the portable class having a self-sustaining main frame-
work and relatively movable parts of a type-
writing machine supported on said frame-
work, a one-piece decorative encircling mask
80 pressed from sheet-metal and spaced from
the inner framework and having side walls
and a rear wall enclosing said framework,
and having a bottom, said side walls having
inwardly-extending flanges, and a lining of
85 sound-absorbing material on the inner faces
and bottom of said mask, to enable them to
co-operate to form a sound-absorbing pocket,
said bottom being fixed to said flanges and
extending from the rear forwardly but leav-
ing an open space at the forward end of the
90 mask, and removable feet having means for
fastening said base to said framework.

12. A compacted typewriting machine of the portable class, including movable type-
writing mechanism and also including an
entirely self-supporting main skeleton fram-
ing whereon said movable mechanism is
100 mounted, said framing including skeleton
side frames, and said machine including a
decorative mask for both said framing and
said mechanism, said mask pressed from thin
sheet-metal and including opposite side
105 members for masking said side frames, sound
subduing linings between said side members
and said side frames, and also including a
key-board-surrounding portion extended for-
wardly from said side portions and having
110 rolled-over stiffening edges, said side mask-
ing portions joined at the front by a front
masking portion, all of said masking portions
being structurally independent of said
framing and encasing the same and attached
thereto.

13. A compacted typewriting machine of the portable class, including movable type-
writing mechanism and also including an
entirely self-supporting main skeleton fram-
ing whereon said movable mechanism is
120 mounted, said machine including a decorative
mask for both said framing and said
mechanism, said mask pressed from thin
125 sheet-metal and including side portions
masking the sides of said frames, and having
a front masking portion extending down-
wardly from the front of said frames and
130 having an extension around and forwardly
of said keys, said mask being struc-

- sheet-metal and including opposite side members for masking said side frames, and also including a keyboard-surrounding portion extended forwardly from said side portions and having rolled-over stiffening edges, said side masking portions joined at the front by a front masking portion, all of said masking portions being structurally independent of said framing and encasing the same and attached thereto, said side portions having inturned flanges, and means for attaching said mask to said framing.
14. A compacted typewriting machine of the portable class, including movable typewriting mechanism and also including a self-supporting main skeleton framing whereon said movable mechanism is mounted, said framing including skeleton side frames, and said machine including a decorative mask for both said framing and said mechanism, said mask pressed from thin sheet-metal and including opposite side members for masking said side frames, and also including a keyboard-surrounding portion extended forwardly from said side portions and having rolled-over stiffening edges, said side masking portions joined at the rear by a rear masking portion and also joined at the front by a front masking portion, all of said masking portions being structurally independent of said framing and encasing the same and attached thereto, said side portions having inturned flanges, and means for attaching said flanges to said side frames, said case also having a bottom bracing portion, and said sides, said rear portion and said bottom portion having a sound absorbing lining to enable them to co-operate to form a sound-confining and subduing pocket.
15. A typewriting machine of the portable class provided with relatively movable parts including a platen and keys, skeleton self-sustained side frames for supporting the same, said keys occupying a position in front of the skeleton frames, and a surrounding casting complementary to said skeleton frames and shaped to embrace the frames but spaced from the sides thereof and constituting an outer decorative mask for the portable typewriting mechanism, said mask being pressed from thin sheet-metal and having inturned flanges at its edges and including side portions masking the sides of said frames, a back portion masking the rear of said frames, and a front masking portion extending downwardly in front of said frames and having an extension around and forwardly of said keys, linings of sound-deadening fibrous material being provided upon the side and rear walls of said mask to enable them to co-operate to form a sound-absorbing enclosure, said mask being structurally independent of said frames, and means for securing the mask upon said skeleton frames.
16. A typewriting machine of the portable class having a double frame including a self-sustaining skeleton main portion, relatively movable typewriting mechanism being supported on said main frame portion, and also including a decorative encircling mask portion formed from sheet-metal and with its sides separated and spaced from the structure of said main portion and including side and rear walls and a front enclosing said main portion, said side walls having inwardly-extending under flanges, a transverse member for attachment to both said flanges to connect and support said side walls, and means for securing together said transverse member, said flanges and said main frame portion.

ALFRED G. F. KUROWSKI.
